HANDLE FOR KITCHEN TOOLS OR SIMILAR ARTICLES

Richard S. Latham, Chicago, Ill., assignor to Ekco Products Company, Chicago, Ill., a corporation of Delaware

Filed July 5, 1961, Ser. No. 65,817

Term of patent 14 years

(Cl. D44—29)

FIG. 1 is a front elevation of a handle for kitchen tools or similar articles showing my new design.

FIG. 2 is an elevational view thereof as the article appears when viewed from the right hand side of FIG. 1.

FIG. 3 is a rear elevational view thereof.

FIG. 4 is an elevational view thereof as it appears when viewed from the left hand side of FIG. 1.

FIG. 5 is a front end view taken in the direction of arrows 5—5 shown in FIG. 1.

FIG. 6 is a section taken along line 6—6 of FIG. 3.

FIG. 7 is a section taken along line 7—7 of FIG. 3.

FIG. 8 is a rear end elevational view of the article taken in the direction of the arrows 8—8 shown in FIG. 3.

I claim:

The ornamental design for a handle for kitchen tools or similar articles, as shown.
